Primary Examiner — Susan Bennett Hattan*Assistant Examiner* — Brett Miller(74) *Attorney, Agent, or Firm* — Knobbe, Martens, Olson & Bear, LLP(57) **CLAIM**

The ornamental design for a snuff box, as shown and described.

DESCRIPTION

The sole FIGURE is a plan view of a snuff box showing the new design.

The surfaces or portions of the snuff bags that are not shown in the drawing or described in the specification form no part of the claimed design. The broken line portion of the claimed design is included to show unclaimed subject matter only and forms no part of the claimed design.

1 Claim, 1 Drawing Sheet(56)
